UNITED STATES PATENT OFFICE.

JOSEPH P. LEGGETT, OF CARTHAGE, MISSOURI.

RAILWAY-CAR.

1,073,429.

Specification of Letters Patent. Patented Sept. 16, 1913.

Application filed February 17, 1913. Serial No. 748,844.

To all whom it may concern:

Be it known that I, JOSEPH P. LEGGETT, a citizen of the United States of America, and a resident of Carthage, in the county of Jasper and State of Missouri, have invented certain new and useful Improvements in Railway-Cars, of which the following is a full, clear, and exact description, reference being had to the accompanying drawings, 10 forming part of this specification.

My invention relates to railway car construction and more particularly to the construction of cars for use upon street railways, the invention having for its object to 15 furnish a car in which there will be at one time a maximum of passenger space, with all of the passengers or the major number of passengers standing, and with provision for seating accommodation of passengers when 20 there is no necessity for the maximum car capacity.

The incentive for my present invention is found in necessity for the transportation by railway companies, especially street rail- 25 way companies, of large numbers of people from or to points of congregation, and under the condition where such people are desirous of transportation with slight delay even at the discomfort of standing in the 30 conveyance furnishing the transportation. As illustrations of points of such congrega- 35 tion I would mention ball parks, fairs of various kinds, and places of amusement in general, where large numbers of people con- gregate.

Figure I is a view illustrating a portion of a railway car in horizontal section constructed in accordance with my invention. Fig. II is a longitudinal, vertical section of 40 the structure illustrated in Fig. I.

Instead of using, in my car, the usual fixed, permanent seats, I utilize convertible seats which may at one time serve as seats for the passengers of the car when there 45 is no necessity for taxing its capacity, and which may at another time, when there is necessity for utilizing the car to its maximum or approximate maximum capacity, be adjusted to positions that will afford greater 50 standing room for the passengers, and furnish means which may be grasped by them for support.

In the accompanying drawings: 1 designates the side walls of a railway car of ordinary construction.

2 designates stationary uprights extend-

ing transversely from the car side walls and preferably spaced equi-distant from each other similarly to the spacing of the backs of seats as ordinarily arranged in railway 60 cars. These uprights have a triple function, in that they serve at one time as partitions creating sub-divisions of the space within the car, and also as supports which may be grasped by passengers while standing between the uprights; and serve at another time as means for supporting seat bottoms adjusted thereto, and as back members against which passengers may rest when occupying the seat bottoms. The uprights are 65 provided with front and rear shoulders or lips 3 having utility to be hereinafter specified.

4 designates vertical risers permanently positioned between the uprights 2, and equi- 70 distant therefrom. These risers are of a height corresponding approximately to the elevation of the bases of seat bottoms as ordinarily present in railway cars.

5 are seat bottoms hinged or pivoted to 80 risers 4 and adapted to be disposed in vertical positions, thereabove, parallel with the uprights 2, or in horizontal positions between the risers and uprights, so that the seat bottoms may at one time serve as supports for passengers standing between the uprights 2 and the risers 4 and the seat bottoms arranged vertically above the latter, while at another time, when the seat bottoms are horizontally positioned and resting on the ledges 3, they will serve in conjunction with the uprights 2 and risers 4 to constitute seats which may be occupied by passengers.

In the illustration, Fig. I, the seat bottoms 95 5 are all disposed vertically and as a consequence the car with the seat bottoms so disposed affords a maximum carrying capacity for passengers who may stand between the risers 2 and the seat bottoms, with opportunity for each passenger to grasp and hold a support when riding in the car, the support being either one of the uprights or one of the vertically disposed seat bottoms.

It will be apparent that by the construction described I furnish narrow compartments between the uprights and risers in each of which only a single row of passengers may stand, so that all passengers are provided with supports which may be 100 grasped by them while facing the front of the car, and without any opportunity of

the passengers being crowded when standing between the uprights and risers.

It is obviously necessary in the construction of my car to furnish means by which the seat bottoms may be held in vertical positions when they are utilized as supports for standing passengers and any suitable means for holding them in vertical positions may be utilized. Inasmuch, however, as I preferably provide for the seat bottoms being adjusted into horizontal positions at either side of the risers supporting them to receive support by either of the uprights 2, I preferably provide seat bottom holding means that will readily engage the seat bottoms when they are elevated from either side of the risers they are pivotally connected to. The means shown in the drawings comprise spring actuated latches 6 the free ends of which are presented toward each other for the purpose of engaging and firmly sustaining the seat bottoms in vertical alinement with the risers beneath them. The latches 6 are mounted in suitable supports therefore secured to the side walls of the car, and it will be obvious that, if needed, similar seat bottom holding means may be provided to engage the edges of the seat bottoms farthest removed from the walls of the car.

30 I claim:—

1. In a car, the combination of permanently positioned uprights spaced from each other, permanently positioned risers between said uprights, seat bottoms movably fitted to said risers, the said seat bottoms being adjustable to horizontal positions between the risers and uprights and into vertical alinement with said risers, and means for holding the seat bottoms in vertical alinement with said risers.

2. In a car, the combination of permanently positioned uprights spaced from each other, permanently positioned risers between said uprights, seat bottoms movably fitted to said risers and adjustable in either direction therefrom to horizontal positions

between the risers and either of two uprights adjacent to the risers to which the seat bottoms are fitted, the seat bottoms being also adjustable into vertical alinement with said risers, and means for holding the seat bottoms in vertical alinement with said risers.

3. In a car, the combination of permanently positioned uprights spaced from each other, permanently positioned risers between said uprights, seat bottoms movably fitted to said risers, the said seat bottoms being adjustable to horizontal positions between the risers and uprights and the uprights being provided with means for supporting the seat bottoms when the seat bottoms are adjusted thereto, the said seat bottoms being also adjustable into vertical alinement with said risers, and means for holding the seat bottoms in vertical alinement with said risers.

4. In a car, the combination of permanently positioned uprights spaced from each other, permanently positioned risers between said uprights, seat bottoms pivoted to said risers and adjustable to horizontal positions between the risers and said uprights, the seat bottoms being also adjustable into vertical alinement with said risers, and means for holding the seat bottoms in vertical alinement with said risers.

5. In a car, the combination of permanently positioned uprights spaced from each other, permanently positioned risers between said uprights, seat bottoms pivoted to said risers and movable into horizontal positions at either side of the risers to which they are pivoted and into engagement with uprights adjacent to said risers, the said seat bottoms being also adjustable into vertical alinement with said risers, and latch devices for holding the seat bottoms in vertical alinement with said risers.

JOSEPH P. LEGGETT.
